[37] CLAIM

The ornamental design for a combined clock face and support, substantially as shown and described.

DESCRIPTION

FIG. 1 is a left front perspective view of a combined clock face and support showing my new design;

FIG. 2 is a front elevational view thereof;

FIG. 3 is a left side elevational view thereof, the right side, not shown, being a mirror image thereto;

FIG. 4 is a left front perspective view of a second embodiment of my new design;

FIG. 5 is a front elevational view thereof; and

FIG. 6 is a left side elevational view thereof, the right side, not shown, being a mirror image thereto.
